CLAIM

The ornamental design for a combined printer and paper-holding slide as shown.

DESCRIPTION

FIG. 1 is a perspective view of a combined printer and paper-holding slide showing my new design.

FIG. 2 is a front elevational view thereof;

FIG. 3 is a rear end elevational view thereof;

FIG. 4 is a side elevational view of the right side of FIG. 1;

FIG. 5 is a side elevational view of the left side of FIG. 1;

FIG. 6 is a top plan view thereof; and

FIG. 7 is a bottom plan view.
